BYRON C. RIBLET, OF SPOKANE, WASHINGTON

CABLE GRIP

Application filed February 18, 1929. Serial No. 340,724.

My present invention relates to improvements in cable grips which while capable of various uses, are particularly designed for use with overhead traveling conveyers for industrial plants, as for instance at mines, for conveying material from the mines to the railroad for transportation. The invention is applied to the grip device for the traction cable of the overhead conveyer, and the grip-10 per or gripping device is of that type utilizing a pair of gripping jaws that are spring pressed, and one of which is laterally slidable relative to the stationary jaw and the traction cable. The slidable jaw is operated or 15 opened by the use of a wedge device, and the latter is actuated by automatic grip control devices, as stops and ramps, located in the path of the wedge device alongside the suspension cable of the overhead conveyer. 20 These control devices are usually located at side-track or turn-out switches, and at loading and unloading stations, for releasing the jaws of the grip from the traction cable and for applying the jaws to the cable. 25 The invention consists in certain novel combinations and arrangements of parts as will hereinafter be more fully pointed out and claimed. In the accompanying drawings I have illustrated one complete example of the 30 physical embodiment of my invention wherein the parts are combined and arranged according to the best mode I have so far devised for the practical application of the principles of my invention. While I have illustrated a 35 conveyer bucket with a pair of trolleys and hangers and with duplex gripping devices on the hangers, it will be understood that the cable grip of my invention may be used as a single unit or a single hanger or frame for 40 the bucket or conveyer, and of course different types of conveyers and trolleys may be substituted for those in the drawings.

Figure 1 is a view in side elevation of one 45 of the conveyers or traveling buckets, equipped with a pair of grips of my invention, and illustrating a grip-releasing ramp which is of sufficient length to hold released both of the grips, when the conveyer unit rides up on 50 the ramp.

Figure 2 is an end view of the conveyer unit of Figure 1 as seen from the right end.

Figure 3 is a detail rear view showing the movable wedge-block and lower end of the wedge of the grip. 55

Figure 4 is an edge or end view showing part of the grip device of Figure 2, but with the grip open or partially open.

Figure 5 is an enlarged detail view in elevation showing the wedge roller and wedge, 60 and the spring pressed retaining lever arm for the wedge.

Figure 6 is a view as seen from the right of Figure 5, some parts omitted and some 65 parts in section.

Figure 7 is an enlarged side view of the grip with the jaws closed, and Figure 8 is a horizontal section at line 8—8 of Figure 7.

In order that the general arrangement and utility of parts may readily be understood I have shown in Figure 1 a portion of the upper, suspension cable 1 and a portion of the traction or power cable 2 of an overhead railway of the cable type, the traction cable being located below the suspension cable, and both members being supported or suspended in appropriate manner, as from towers or poles. 75

The conveyer unit includes a dump bucket 3 with its hinged bottom 4, and the bucket is suspended by hangers 5, the hangers being connected by a reach rod 6 having hooked ends in perforated lugs or ears 7 on the respective hangers. The hangers and rod form a suspending frame for this type of bucket, 80 and the frame is pivotally supported at 5' on two trolley frames 8 and 9 that are equipped with pairs of trolley wheels 10 arranged in tandem fashion. 85

The aligned trolleys of course roll or travel 90 along on the suspension cable, and each of the hangers 5 is equipped with a cable-grip device of the wedge operated type for gripping the traction cable 2. Inasmuch as the grip devices are of duplicate construction a description of one device will suffice for both devices. 95

As best seen, in Figures 7 and 8, the hanger 5 is fashioned with a lateral integral or rigid boss 11, which terminates at its outer end in 100

a fixed or stationary grip-jaw 12, and a movable jaw 13 is associated with this fixed jaw to grip the traction cable 2, both of the jaws being grooved or notched as at 14 to facilitate the gripping action. The movable jaw is mounted on the ends of a pair of parallel bolts 18 that are slidable longitudinally in the boss 11, and between the fixed jaw and the movable jaw a tension spring 16 is located for the purpose of projecting the movable jaw to the right in Figures 7 and 8 when permitted to do so, for the release of the jaws from the cable.

The bolts are threaded at one end in the movable jaw, and at their other ends a wedge block 17 is secured, it being understood that the movable jaw and the block move with the slidable bolts, nuts 18 being used on the bolts to retain the wedge block.

At its inner side the wedge block is fashioned with two angular wedge faces 19 and 20 and these faces are located in spaced relation to a wear block 21 that is securely carried in a socket in the face of the hanger 5.

The jaws are gripped on the cable by the action of a downwardly movable wedge bar 27 as it passes in between the bearing block or wear block 21 and the wedge faces of the wedge block to draw the movable jaw toward the fixed jaw. This wedge bar has at its lower end a pair of wedge faces 23 and 24, disposed at angles complementary to the two faces of the wedge block, so that as the wedge bar descends to close the grip the faces 24 and 20 will engage with a comparatively slight friction or guiding movement, and then the faces 23 and 19 will engage with a greater degree of friction to positively close the grip, and this greater friction prevents the wedge bar from being displaced by vibrations due to travel of the conveyer unit. The wedge bar is thus lowered to close the grip, and means are provided whereby the bar is raised when the grip is to be opened or released.

At the upper end of the wedge bar a pair of side plates 44 are bolted and these spaced plates form an open guide frame for the wedge bar, which frame straddles a guide pin 25 rigid with the trolley frame, to enable the wedge bar to rise and fall without lateral displacement. Above the guide pin a pair of bolts 26 tie the plates together and tubular spacers or pipe sections 22 are interposed between the plates. A washer 28 is mounted on the outer end of the pin, and a cotter pin 29 in the pin holds the washer lightly against the outer edges of the side plates to prevent wobbling of the wedge.

For vertically reciprocating the wedge bar an anti-friction roller or wedge-roller 30 is journaled on a stud shaft 31 that is mounted in a bearing block 32, bolted within the space between the side plates, and at the opposite side of the wedge bar a retaining roller 33 is

journaled on the stud shaft. For co-action with this retaining roller a retaining lever arm 34 is pivoted at 35 at one side of the wedge bar, and, with a compound curve, this lever arm extends back of and across the wedge bar, in contact with the retaining roller. A spring 36 is anchored to the free end of the retaining lever arm, and at 37 one end of the spring is connected to a part of the hanger 5. Thus the pivoted end of the lever arm is supported on the hanger and one end of the spring is anchored to the hanger, in order that the lever arm may, with a resilient pressure on the retaining roller, hold the wedge bar in place, to prevent its dislocation.

The wedge bar is lifted by means of a stationary ramp 38 in Figure 1 when the conveyer unit travels to the right and the wedge roller 30 rides up and along the ramp, and the wedge bar on the following trolley is lifted in the same manner. When the roller 30 encounters the ramp and rides upwardly as indicated, the wedge bar is lifted and the wedge faces at the end of the bar are lifted to released position in Figure 4. This displacement of the lower end of the wedge bar permits the spring 16 to project the movable jaw 13 so that the traction cable may fall from the grip. It will be understood that the retaining spring 36 has sufficient strength to hold the wedge bar in place, but has not sufficient strength to overcome the friction of the wedge parts and force them apart.

For lowering the wedge bar to lock the grip or grip the jaws on the cable, I may employ a weighted or gravity ramp 39 having two cam faces, and pivotally supported at one end as at 40. At its opposite free end, the ramp is suspended by a slotted link 41, the slot 42 in the link co-operating with a bolt or pin 43 to guide the vertical swinging movement of the overhead, gravity, ramp. The normal, lowered position of this ramp is indicated by dotted lines, and the weight of the suspended ramp is sufficient to bear down on the wedge roller when the latter encounters the ramp, in order that the wedge bar shall be depressed to gripping position. The purpose of this movable ramp is to compensate for different sizes of traction cable with which the grip coats. Sometimes the diameter of the cable is reduced, due to wear, and sometimes a cable of different diameter is substituted for the original cable. This difference is taken care of or compensated for by the use of the weighted, but movable ramp.

Usually the gripping ramp is located down an incline of the suspension cable so that the conveyer unit may run down the incline a distance sufficient to insure the momentum required to depress the wedge bar and grip the cable. In this manner the traveling unit is gripped to the traveling traction cable and unnecessary jerks are avoided when the gripping action takes place.

Having thus fully described my invention, what I claim as new and desire to secure by Letters Patent is:—

1. In a cable grip the combination with a support forming a stationary jaw, of a movable jaw slidably mounted in the support and a spaced wedge block rigid with the movable jaw, a wedge operable between the wedge block and a portion of the support, and means for operating the wedge. 5 70
2. In a cable grip the combination with a support forming a stationary jaw, of a pair of slide bolts mounted in the support and a movable jaw rigid with the bolts, a spaced wedge block mounted on the bolts, a wedge operable between the block and support, and means for operating the wedge. 15 75
3. In a cable grip the combination with a support forming a stationary jaw, of a pair of spaced, parallel bolts slidably mounted in the support, a jaw secured on said bolts and an expansion spring interposed between said jaws, a wedge block, a wear block on the support, and a reciprocable wedge operable between said blocks. 20 80
4. In a cable grip the combination with a support forming a stationary jaw, of a laterally movable jaw and wedge mechanism for closing said jaws, said mechanism including a wedge bar, and resilient means for retaining said wedge bar in operative position. 25 85
5. In a cable grip the combination with a support forming a stationary jaw and a laterally movable jaw, of a wedge block movable with the latter jaw, a reciprocable wedge bar and guides therefor, and an anti-friction roller mounted on the wedge bar. 30 90
6. In a cable grip the combination with a hanger, a boss thereon forming a jaw, a laterally movable jaw supported on the boss and a spaced wedge block movable with the jaw, of a support for the hanger, a reciprocable wedge bar suspended from said support, and means for depressing the wedge bar to close said jaws. 35 95
7. In a cable grip, the combination with a hanger and a fixed jaw mounted thereon, a complementary, movable jaw supported on the hanger and a wedge block movable with that jaw, of a support for the hanger, a reciprocable wedge bar suspended from said support, means for depressing the wedge bar, a wedge roller on the bar, a retaining roller on the bar, a retaining lever pivoted at one end to the hanger and engaging the retaining roller, and a spring connecting the free end of the retaining lever with the hanger. 40 100
8. In a cable grip of the wedge type, the combination of a support and a hanger suspended therefrom, of a vertically reciprocable wedge bar suspended from the support and means on the bar for co-action with a ramp, a retaining roller journaled on the bar, and a spring retaining lever-arm mounted on the hanger and co-acting with said roller. 45 105
9. In a cable grip of the wedge type, the combination of a support and a suspended hanger, of a vertically reciprocable wedge bar suspended from the support, a wedge roller journaled on the bar for co-action with a ramp, a retaining roller journaled on the bar, a lever arm pivoted at one end on the hanger and frictionally engaging the retaining roller, and a spring connecting the free end of the arm with said hanger. 50 110
